UNITED STATES PATENT OFFICE.

MENNO S. PRICE, OF SANTA CRUZ, CALIFORNIA.

KILN.

Application filed March 17, 1926. Serial No. 95,394.

This invention relates to improvements in kilns and has particular reference to a kiln adapted to be used in the preparing of cement. It is obvious, however, that the same 5 kiln may be employed in many other places.

The principal object of this invention is to produce a kiln having two inclinations thereby permitting a slow travel of the raw material through the first portion of the kiln and 10 later accelerating the rate of travel through the latter portion of the kiln.

Another object of this invention is to increase production per kiln.

An additional object is to produce a kiln 15 having a greater heating area at the point at which the raw material is introduced and to further permit a greater transfer of heat to the material, thus saving in fuel and stack losses.

20 A still further object is to slow up the velocity of gas with its resultant transfer of heat to the material in the kiln.

Another object is to produce a kiln wherein a large volume of material may be treated, 25 thereby increasing the grinding effect always present in a rotary kiln.

Further objects are to eliminate mud rings at the feed end of the kiln which elimination is accomplished by virtue of the funnel-shaped kiln having a larger diameter and, 30 consequently, less arching effect which construction serves to minimize mud ring troubles; and due to the mass of materials in the funnel-shaped section greater mixing 35 is accomplished thereby improving the product.

Other objects and advantages will be apparent during the course of the following description.

40 In the accompanying drawings forming a part of this specification, and in which like numerals are employed to designate like parts throughout the same,

Figure I is a side elevation of a kiln constructed in accordance with my invention, and

Figure II is a diagrammatic view showing the various inclinations of the kiln with respect to the axis of the kiln.

50 In the burning of material for cement, it has been common to employ a kiln having but one inclination, the result being that the material carried through the kiln had a uniform speed. By constructing a kiln with two in-

clinations, it is possible to effect a large quantity of material to the kiln and due to its initial slow travel through the kiln, a large amount of heat is absorbed from the hot gases passing through and to finally discharge the material in a relatively thin stream which can then be properly burned.

In the accompanying drawings wherein for the purpose of illustration is shown a preferred embodiment of my invention, the numeral 5 designates a throat which provides 65 the inlet end of the kiln and to which is secured a funnel like member 6. This member 6 has connected thereto a kiln section 7. This kiln section 7 is tapered and is supported in the customary manner as by rings 11, 12 and 70 13 which travel upon rollers positioned in bearing blocks 14, 16 and 17, respectively.

These bearing blocks are mounted upon any surface such as designated by the ground line 18. In order to turn the kiln, I have 75 shown a gear 19 secured thereto, with which a gear 21 meshes. This gear 21 is connected by a shaft 22 from any suitable source of power.

At 23 I have shown a kiln section cylindrical in form and connected to the kiln section 7 as at 24. At 26 I have shown a supporting ring which travels upon rollers mounted in the bearing block 27. The free end of the kiln section 23 constitutes the outlet end of 85 the kiln and this section is much shorter than the section 7.

Referring now to Figure II, the broken line A—B designates the axis of the kiln, the line C—E the inclination of the cylindrical portion 23 of the kiln with respect to the floor line, the line E—F the surface of the portion 7 of the cone or inclination of this surface, with respect to the axis. The line F—G designates the surface of the funnel or inclination thereof, with respect to the axis and the line G—D the surface of the throat with respect to the axis.

It will, therefore, be noted that the material entering the throat 5 will quickly be discharged down the inclined surface of the funnel where it will come into contact with the kiln section 7.

As the inclination of this portion of the kiln represented by the line E—F is less than 105 the inclination of the axis represented by the line A—B, the travel, due to the rotary movement of the kiln, through this portion of the

5 kiln will be much slower than if the inclination were the same as that of the axis. This results in the material within this portion of the kiln receiving a longer treatment or pre-heating, than would otherwise be possible.

10 This pre-heating is brought about by the fact that the volume of the kiln at this point being greater, a larger quantity of hot gases are present which transfer their heat to the material within the cone. As the material within the cone reaches the point E, it will pass into the cylindrical portion of the kiln which has the same inclination as the axis.

15 This will cause the material to travel at a greater rate thereby being thinned out and capable of absorbing a greater quantity of heat which places the same in proper condition to be burned.

20 It will thus be seen that I have produced a kiln which will accomplish all of the objects above set forth.

25 It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention, I claim:

30 A rotary inclined kiln comprising a relatively long tapered section, a funnel like member having its large end formed with the large end of said tapered section, a throat of 35 cylindrical formation and being formed with the opposite end of the funnel like member, said throat providing the inlet end of the kiln, a relatively short cylindrical section having one end secured to and in communication with the small end of said long tapered section and its opposite end constituting the outlet end of the kiln, said outlet end being disposed below the inlet end, means for rotatably supporting the sections at an inclination with their longitudinal axis in alignment whereby the wall of the cylindrical section will be disposed at a greater inclination with respect to the ground than the wall of the tapered section so that material in passing through the kiln will move relatively 40 slow through the tapered section and increase in movement when passing through the cylindrical section with the result the material will be subjected to heat accordingly, and 45 means for rotating the sections.

50 In testimony whereof I affix my signature.
